UNITED STATES PATENT OFFICE.

JOHN A. WHITTINGTON, OF DARLINGTON, SOUTH CAROLINA.

UMBRELLA.

No. 828,990.

Specification of Letters Patent.

Patented Aug. 21, 1906.

Application filed November 7, 1905. Serial No. 286,227.

To all whom it may concern:

Be it known that I, JOHN A. WHITTINGTON, a citizen of the United States, residing at Darlington, in the county of Darlington 5 and State of South Carolina, have invented new and useful Improvements in Umbrellas, of which the following is a specification.

My invention has relation to new and useful improvements in umbrellas; and it consists of providing an umbrella with improved locking means and using in conjunction therewith a detachable handle, said handle and locking means serving to lock and unlock said umbrella.

15 It is a well-known fact that the stealing of umbrellas is of daily and frequent occurrence; and the object of my invention is to provide an umbrella with means to lock same when the handle is detached, and thus make 20 the umbrella undesirable to one not in possession of the handle, and should the umbrella be taken by mistake (which is improbable, the handle being absent) the party's attention will be called to this fact 25 when he attempts to open the same. The owner is to detach the handle and take it with him when he leaves the umbrella.

In the accompanying drawings, Figure 1 is 30 a vertical sectional view of an umbrella-rod and detachable handle, partly in section, said rod and handle being provided with my improved locking means. Fig. 2 is a view of a key which is used in connection with my invention. Fig. 3 is a view of a rod used in 35 connection with my invention. Fig. 4 is an outside view of a tube which is secured in the lower end of the detachable handle, having a band at its lower end to encircle the handle. Fig. 5 is a detail sectional view showing the 40 lower part of the detachable handle, a sectional view showing the inside of the tube shown in Fig. 4 and an edge view of the key, which is secured in upper end of said tube. Fig. 6 is a view showing the upper part of an 45 umbrella-rod extending into the lower part of the wood handle 10 and there secured to the tube 7. Fig. 7 is a view showing the upper end of tube 7 provided with a keyhole. Fig. 8 is a detail view showing the spring 19 50 attached to the rod shown in Fig. 3.

My invention is described as follows: The handle 1 is hollow at its lower end. A tube 2 is secured in the hollow of said handle. Said tube is provided with a vertical groove 3, terminating in a groove 4 almost at right angles 55 to said groove 3, but slanting up a little, giv-

ing an obtuse angle of about one hundred degrees. Said tube is also provided with a band 5, which encircles the lower end of the handle. The grooves 3 and 4, above described, are made by pressing the wall of said tube 2 from the inside outwardly. A tube 7 is secured to the hollow umbrella-rod 8 and is provided on its outer face and near its upper end with a projection 9, which runs 60 up the groove 3 and into groove 4 on tube 2. The lower and upper ends of lower wood handle 10 are provided with bands 11. A key 12 is rigidly secured in the upper part of the tube 2 and extends downwardly to near the bottom of said tube. A locking-rod 13, which has on its upper end a screw-head 14 and on its lower end a lug 15, provided with a slot 16, is fitted in the umbrella-rod 8. The screw-head 14 of said locking-rod rests on the upper 75 end of said umbrella-rod 8 and the lower end extends downwardly until the slot 16 in the lug 15 may be brought to register with the umbrella-dog 18. Said locking-rod has secured to it a spring 19 to keep it from turning 80 in umbrella-rod until sufficient pressure is applied.

When it is desired to removably secure the handle to the umbrella, said handle is brought in position and turned to the right 85 or left until the lower end of said vertical groove 3 (there may be one or more of said vertical and angle grooves) in tube 2 registers with said extension (or extensions) 9 on tube 7. Then sufficient pressure is brought 90 to bear on the handle to cause said extension (or extensions) to ride up in said groove (or grooves) until it reaches the point where said groove turns horizontally, forming a horizontal groove 4. Said handle is then 95 turned to the right, causing said extension 9 to ride in horizontal groove 4 until said handle is secured tightly in place and until its lower end fits snugly and tightly against the upper end of lower wood handle 10, which 100 surrounds umbrella-rod 8, and lower part of tube 7. The horizontal part 4 of groove 3 is made at an angle of about one hundred degrees in order that said handle may become secure when same is turned about half 105 around. When said handle is in position, the lower end of key 12, which has passed through keyhole 6 in tube 7, is received in notch 20 in the screw-head 14 of the locking-rod 13, and when said handle is turned said locking-rod 110 is thereby caused to rotate until the slot 16 in lug 15 in lower end of said locking-rod

registers with the ordinary umbrella-dog 18. Then the umbrella can be opened or closed at will.

The umbrella cannot be opened when handle is detached, as the umbrella-dog 18 cannot be depressed or forced into umbrella-rod 8 except when slotted side of lug 15 registers with said dog.

The grooves in the said tube 2 are made in different lengths and in different positions in said tube, so that the handles are not interchangeable.

When the handle is brought into position to be removed, the solid part of the lug 15 is thereby turned under the slot 7 in the rod 8, and therefore immediately under the umbrella-dog 18, and the umbrella is locked.

Having described my invention, what I claim as new, and desire to secure by Letters 20 Patent, is—

1. The combination of the handle 1, having in its lower end a hollow; a tube 2, having in its upper end a perforation, and in its side a vertical groove 3, and a horizontal groove 4, and attached to its lower end a band; said tube inserted in said hollow; a tube 7, having in its upper end a keyhole 6, the lower end of said tube secured to the upper end of the umbrella-tube 8, its upper end 25 extending up into the tube 2; a rod 13, fitting in said umbrella-tube 8, and having on its lower end a slotted lug 15, and on its upper end a screw-head 14, the screw-head 14, resting on the upper end of the umbrella-tube 8; 30 a key 12, its head rigidly secured to the upper face of the head of the tube 2, its blade passing down through the upper ends of said tubes 2 and 7, its lower end fitting in a notch 35

20, of the screw-head 14; a dog 18, secured to the umbrella-tube and adapted to slide in 40 and out of the slot 16, of the lug 15; a spring 19, secured at its middle to the rod 13, its outturned ends resting against the inner face of the umbrella-tube 8, and a wooden-handle extension 10, encircling and secured to the 45 lower end of tube 7, and the upper end of umbrella-tube 8, substantially as shown and described and for the purposes set forth.

2. The combination of the handle 1, hollow at its lower end; the tube 2, having a vertical groove 3, terminating in a groove 4, nearly horizontal, inserted in said hollow; a tube 7, having in its upper end a keyhole 6, the lower end of said tube secured to the upper end of the umbrella-tube 8, its upper end 50 extending up into said tube 2; a rod 13, fitting in said umbrella-tube, and having on its lower end a slotted lug 15, and on its upper end a screw-head 14, said screw-head resting on the upper end of said umbrella-tube; a 55 key 12, its head rigidly secured to the upper face of the head of the tube 2, its blade passing down through the upper ends of said tubes 2 and 7, its lower end fitting in the screw-head 14, and a dog 18, secured to the 60 umbrella-tube and adapted to slide in and out of the slot 16, of the lug 15, substantially as shown and described and for the purposes set forth.

In testimony whereof I affix my signature 70 in presence of two subscribing witnesses.

JOHN A. WHITTINGTON.
